Primary Examiner — Eric L Goodman*Assistant Examiner* — Sarah L Smith*(74) Attorney, Agent, or Firm* — Brett M. Pinkus(57) **CLAIM**

The ornamental design for a lantern, as shown and described.

DESCRIPTION

FIG. 1 is a front perspective of a lantern showing our new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof; and,
FIG. 8 is a front perspective of a lantern showing our new design, with a compartment door in an open position to reveal a compartment having a power outlet and electronic interface.
Portions of the lantern are shown in broken lines, and is for illustrative purposes only and forms no part of the claimed design.

1 Claim, 8 Drawing Sheets(56)
